DESIGN FOR A CANDLE OR THE LIKE

Erna von Bilkau, New York, N. Y.

Application January 24, 1940, Serial No. 89,677

Term of patent 3½ years

To all whom it may concern:

Be it known that I, Erna von Bilkau, a citizen of the United States, residing in New York city, in the county of New York and State of New York, have invented a new, original, and ornamental Design for Candles or the like, of which the following is a specification, reference being had to the accompanying drawing, forming part thereof.

I claim:

The ornamental design for a candle or the like, substantially as shown.

ERNA VON BILKAU.
